UNITED STATES PATENT OFFICE.

STEPHEN A. STAEGE, OF PITTSBURGH, PENNSYLVANIA, ASSIGNOR TO WESTINGHOUSE ELECTRIC & MANUFACTURING COMPANY, A CORPORATION OF PENNSYLVANIA.

SPEED-REGULATOR SYSTEM.

Application filed September 2, 1921. Serial No. 497,816.

To all whom it may concern:

Be it known that I, STEPHEN A. STAEGE, a citizen of the United States, and a resident of Pittsburgh, in the county of Allegheny and State of Pennsylvania, have invented a new and useful Improvement in Speed-Regulator Systems, of which the following is a specification.

My invention relates to regulator systems and it has special relation to systems adapted to maintain a substantially-constant speed ratio between a plurality of moving members.

One object of my invention is to provide a speed-regulator system of the above-indicated character which shall be inexpensive in construction and simple and efficient in operation.

Another object of my invention is to provide a speed-regulator system of the above-indicated character which shall embody positive-acting means for preventing hunting action on the part of the regulating system.

Another object of my invention is to provide a speed-regulating system of the above-indicated character which shall have a corrective movement in two directions, comprising one movement in the direction to secure the needed correction, which movement shall be proportional to the variation to be corrected for, and a second movement opposite to the first movement and proportional to the amount of the preceding corrective movement.

In my copending application, Serial No. 460,838, filed April 12, 1921, is described a speed-regulator system of the above-indicated character wherein each set of rotatable members is propelled by a variable-speed motor. Each rotatable member operates a frequency changer that is electrically connected to one winding of a second frequency changer. The other winding of the second frequency changer is connected to a frequency changer that is common to all of the rotatable members and is adapted to supply a constant frequency. The second frequency changer is, in effect, an electric differential or a differential relay. The electric differential actuates a movable brush, which co-operates with a rotatable commutator cylinder to control a shunt cir-

cuit for a resistor in the circuit of the variable speed motor.

It sometimes happens, in the event of a large corrective movement by the brush, that there is an excessive movement, or an over-regulating effect. Accordingly, in that system, the differential must again operate to move the brush in the opposite direction to make the proper correction in the operation of the variable-speed motor. In other words, there may be a tendency for the regulator system to "hunt."

The present invention has to do specifically with mechanism for automatically returning the brush the necessary amount to insure perfect corrective action.

Reference may now be had to the accompanying drawing, wherein—

Figure 1 is a diagrammatic illustration of circuits and apparatus embodying my invention, as applied to a plurality of rotatable members;

Fig. 2 is a detail view illustrating the frictional connection between the shaft of the differential machine and the pawl-and-ratchet mechanism; and

Fig. 3 is a side elevation of the commutator apparatus, partly in section, in the plane indicated by the line III—III of Fig. 1.

Since the apparatus for the sets of rotatable members are alike, the present invention will be described with reference to a single set, and like parts will be given the same reference numerals.

A set of rotatable members is diagrammatically indicated by a roll 11 which is adapted to be driven by a variable-speed propelling motor 12, having an armature 13 and a field-magnet winding 14, through suitable gearing 15. Through speed-changing apparatus 10, the roll 11 operates the rotor 16 of a frequency changer 17 having a stator 18 winding 19 which is energized from any suitable source.

The rotor or secondary winding 16 is electrically connected to the rotor or secondary winding 19 of a second frequency changer 21, the primary winding 22 of which is electrically connected to the secondary winding 23 of a frequency changer 24, which is common to all of the roll units. Frequency changer 24 has a primary winding 25 which is energized from any suitable

source, preferably the same as that to which the stator winding 18 is connected. Frequency changer 24 is adapted to be driven by the motor 26 to supply a constant frequency to the several frequency changers 21.

It will be apparent that, if the frequencies applied to the secondary winding 19 and the primary winding 22 of the frequency changer 21 are identical, there will be no movement of the shaft 27 of this machine. However, any variations in frequency will be indicated by a rotation of the shaft. Hence, this frequency changer becomes, in operation, a differential mechanism.

15 Mounted upon the shaft 27 are two ratchet wheels 28 and 29, rigidly connected together but frictionally mounted upon the shaft 27 in any well-known manner, one mounting being illustrated in Fig. 2. The 20 frictional mounting comprises a disk 31 that is pressed into engagement with the ratchet 28 by means of a spring 32, which has co-operating therewith, at its opposite end, a washer 33 and lock nuts 34.

25 The ratchet wheel 29 carries a connecting rod 35 having, at its free end, a pair of brushes 36, shown in detail in Fig. 3. Co-operating with the brushes 36 is a commutator cylinder 37 which is mounted upon the 30 shaft 38 of a driving motor 39. Also mounted upon the shaft 38 is a slip-ring 41 which has a brush 42 co-operating therewith and is in electrical engagement with the metallic portion of the commutator cylinder 37.

35 Included in the circuit of the field-magnet winding 14 of the propelling motor 12 is a resistor 43. A shunt circuit for the resistor is completed through the brush 42, connected to one side of the resistor, and the 40 brushes 36, connected to the other side thereof.

In the discussion which will follow, it will be assumed that, with the brushes 36 in the central position indicated in Fig. 1, the 45 resistor 43 will be included in the circuit of the field-magnet winding 14 fifty per cent of the time and excluded from that circuit fifty per cent of the time to maintain the proper speed upon the motor 12, thereby 50 rendering the differential 21 inactive.

Should there be a change in load upon the roll 11, a corresponding change in frequency will occur in the differential 21, thus actuating the ratchets to move the brushes 36 a 55 distance proportional to the load variation and thereby vary the strength of the field-magnet winding 14 to compensate for the load variation. It will be apparent that, if the load variation is small, requiring only a 60 small corrective movement of the brushes 36, there will be no tendency for the brushes to over-run the proper correcting position. Should the load variation be large, requiring a correspondingly large movement of 65 the brushes 36, there will be an increasing

tendency for the brushes to over-run the proper corrective position. To prevent such hunting action, a lever arm 44 is provided, which is pivoted at 45 and is connected to the ratchet wheel 29 through the dash-pot 70 mechanism 49 so as to receive movements proportional to the movements of said ratchet wheel.

The lever arm 44 has mounted thereon, at its fulcrum point, a contact-making arm 46 75 which engages either contact member 47 or contact member 48, as will be hereinafter described. The lever arm 44 has push rods 51 and 52 mounted at the respective ends thereof which respectively engage, at their upper ends, with an extension of the pawls 53 and 54. Pawl 53 co-operates with ratchet wheel 29 and pawl 54 co-operates with ratchet wheel 28.

It will be noted that the ratchet mechanisms operate in opposite directions and that the pawls engage different ratchet teeth in accordance with the positions of the push rods 51 and 52. Each of the pawls has a bell-crank arm 55 secured thereto, the arms each being pivoted as indicated at 56. Mounted upon each arm 55 is an armature 57, co-operating with which are electro-magnets 58 and 59. The energizing coils of the electromagnets 58 and 59 are respectively connected to the contact members 47 and 48 and are adapted to be selectively energized, as will be hereinafter pointed out.

The pawls 53 and 54 are adapted to describe an arcuate movement, in accordance with the rotation of the shaft 27, through the connecting links 61 and 62 which are loosely mounted upon the shaft 27.

In the operation of the mechanism just described, assuming a movement of the brushes 36 toward the left in Fig. 1, and that such movement is excessive, a movement is imparted through the dash-pot 49 to exert an upward pull upon the arm 44 to thus cause the contact-making arm 46 to bridge contact member 48. The circuit to the energizing coil of magnet 59 will then be completed, which will attract the armature 57 to move the associated bell-crank arm 55. In timed relation with this movement, the 105 push rod 52 is lowered to lower the pawl 54. The pawl 54 will engage different teeth on the ratchet wheel dependent upon the degree of movement of the arm 44 and push rod 52. Thus, when the electro-magnet 59 110 is energized to move the pawl 54, the ratchet wheel will move a varying distance dependent upon the ratchet tooth engaged, which, in turn, is dependent upon, and proportional to, the amount of corrective movement required.

Accordingly, when the magnet 59 is energized to move the bell-crank arm 55, which is associated with the pawl 54, the pawl will engage the ratchet wheel 28 to rotate the 125 130

shaft 27 and also the ratchet wheel 29 to thus move the brushes 36 toward the right in Fig. 1. This second movement is adapted to be just sufficient to establish the needed 5 correction of the motor 12.

By reason of the mechanical connections between the shaft 27 and the pawl 54, and between the disk 29 and lever arm 44, the anti-hunting mechanism is returned to its 10 normal inactive position concurrently with the retroactive movement of the brushes 36. This action will also break the circuit of the coil of electromagnet 59, releasing the pawl 54 from engagement with the ratchet wheel 15 28.

Without entering into further detail, it will be apparent that, if the first corrective movement is toward the right in Fig. 1, the downward movement of the dash-pot 46 will 20 effect the opposite movement of the arm 44 to engage the contact arm 46 and contact member 47, thereby completing the circuit to electromagnet 58 and effecting the above-described anti-hunting movements in co-operation 25 with the pawl 53, producing the same results as those previously described in connection with initial movement in the opposite direction.

It should be noted that the degree of anti-hunting correction is not always the same. That is to say, every corrective movement of 30 the brushes 36 requires a movement of the anti-hunting mechanism directly proportional to that corrective movement. With 35 the present system, the proportionality between these movements is maintained in accordance with the variation to be corrected for. Relatively small or slow movements of the brushes 36 require no anti-hunting action and, hence, the dash-pot will permit 40 the anti-hunting mechanism to remain inactive. However, relatively large or quick movements of the brushes 36 will require the anti-hunting mechanism to be operated.

45 Modifications in the system and arrangement and location of parts may be made within the spirit and scope of my invention, and such modifications are intended to be covered by the appended claims.

50 I claim as my invention:—

1. In a speed-regulator system, the combination with a rotatable member, a propelling motor therefor, a resistor in circuit therewith, a frequency changer operated by 55 said member, a constant-frequency source and an electric differential energized in accordance with the two frequencies, of a commutator cylinder and co-operating movable brush circuit-interrupting apparatus adapted 60 to control a shunt circuit for said resistor, said brush being moved in accordance with the operation of said differential, and means adapted to move said brush in a direction opposite to the movement by said differential.

2. In a speed-regulator system, the combination with a motor, a resistor in circuit therewith, a source of constant power, and a differential connected between said motor and said source, of a commutator cylinder 70 and co-operating movable brush apparatus adapted to control a shunt circuit for said resistor, said brush being shifted in accordance with the operation of said differential, and anti-hunting means adapted to move 75 said brush in a direction opposite to the movement imparted by said differential, whereby a proper motor correction is completed.

3. In a regulator system, the combination 80 with a motor, a resistor in circuit therewith, and a differential device associated therewith, of a commutator cylinder and co-operating movable brush apparatus actuated by said differential device and adapted to control the value of said resistor, said brush being moved in accordance with the operation of said differential, and means adapted to move said brush in an opposite direction 85 at predetermined times.

4. In a regulator system, the combination 90 with a dynamo-electric machine, a resistor in circuit therewith, a constant power source and differential means located between said rotatable member and said source, of a mechanism actuated by said differential means adapted to control the value of said resistor and having a corrective movement in two directions, the first movement producing over-regulation, and the second movement counteracting the over-regulation 95 in a degree proportional to the corrective movement.

5. In a regulator system, the combination 100 with a dynamo-electric machine, a resistor in circuit therewith, of means adapted to control the value of said resistor comprising a differential means and means actuated thereby and having a corrective movement in two directions, the first movement being 105 proportional to the variation to be corrected, and the second movement being proportional to the corrective movement.

6. In a speed-regulator system, the combination with a rotatable member, a propelling motor therefor, a resistor in circuit therewith, electric differential means associated with said rotatable member and a commutator cylinder and movable brush circuit-interrupting apparatus operated by 115 said differential and controlling the value of said resistor, of means operable to compensate for excessive corrective movements of said brush.

7. In a speed-regulator system, the combination with a rotatable member, a propelling motor therefor, a resistor in circuit therewith, electric differential means associated with said rotatable member and a commutator cylinder and movable brush 120 125 130

- 2 circuit-interrupting apparatus operated by said differential and controlling the value of said resistor, of pawl-and-ratchet mechanism adapted to compensate for excessive movements of said brush, said mechanism having a movement proportional to the amount of movement of said brush.
8. In a regulator system, the combination with a dynamo-electric machine, a resistor in circuit therewith, and a commutator cylinder and a co-operating movable brush adapted to control the value of said resistor, of means for moving said brush to vary the value of said resistor, and pawl-and-ratchet mechanism adapted to compensate for excessive movements of said brush, both of said movements being in accordance with the variation to be corrected.
9. In a regulator system, the combination with a dynamo-electric machine, a resistor in circuit therewith, and a commutator cylinder and co-operating movable brush adapted to control the value of said resistor, of means for moving said brush proportional to the variation to be corrected, and pawl-and-ratchet mechanism adapted to also move said brush an amount proportional to the first movement of said brush.
10. In a speed-regulator system, the combination with a motor, a resistor in circuit therewith, differential means associated with said motor, and a commutator cylinder and co-operating movable brush operated by said differential means and adapted to control the value of said resistor, of pawl-and-ratchet mechanism adapted to compensate for excessive corrective movements of said brush, a pivoted lever flexibly connected to said mechanism and carrying a contact-making arm and a plurality of push rods adapted to selectively vary the operative position of said pawls, and electromagnetic actuating means for said mechanism energized in accordance with the operation of said contact-making arm.
11. In a regulator system, the combination with a dynamo-electric machine, a resistor in circuit therewith, and a commutator cylinder and co-operating movable brush adapted to control the value of said resistor, of pawl-and-ratchet mechanism adapted to compensate for the excessive corrective movements of said brush, a pivoted lever connected to said mechanism and carrying a contact-making arm and a plurality of push rods which respectively cooperate with said pawl members, and selectively energized electromagnetic actuating means for said pawl members.
12. In a regulator system, the combination with a dynamo-electric machine, a resistor in circuit therewith, control means therefor, and means for governing said control means in one direction, of pawl-and-ratchet mechanism adapted to compensate for excessive operation of said governing means, a pivoted lever connected to said governing means and carrying a contact-making arm and push rods co-operating with said pawls, and electromagnetic actuating means for said mechanism selectively energized by said contact-making arm.
13. In a regulator system, the combination with a dynamo-electric machine, a resistor in circuit therewith, control means therefor, and means for governing said control means in one direction, of pawl-and-ratchet mechanism adapted to compensate for excessive operation of said governing means, a pivoted lever connected to said governing means and carrying a contact-making arm and push rods co-operating with said pawls, said pawls being adapted to receive a movement proportional to the operation of said governing means, and electromagnetic actuating means for said mechanism selectively energized by said contact-making arm.
14. In a speed-regulator system, the combination with a motor and a resistor in circuit therewith, of a commutator cylinder and co-operating movable brush-controlling means for said resistor, means for moving said brush in a direction to correct for variations in the speed of said motor, and pawl-and-ratchet mechanism adapted to return said brush at predetermined times an amount proportional to the amount of the corrective movement.
- In testimony whereof, I have hereunto subscribed my name this 9th day of August, 1921.
- STEPHEN A. STAEGE.
